 6 Claims. (Cl. 92—99)

This invention relates to rolling seal diaphragm devices and diaphragms.

I have discovered an important novel rolling seal diaphragm bistable in top hat configuration (as shown in FIG. 6) and in one convoluted configuration, that not only further reduces wear owing to reduction of convolution stresses but facilitates nested shipping (in the top hat configuration). I provide in a preferred embodiment a diaphragm with a wall defined by revolution about an axis of a line including a pair of arcs of radii extending from opposite sides of the line; the arcs may merge into each other, or they may be spaced, as by a straight line to which both are tangent.

Other features, objects, and advantages of the invention will appear from the following description of a preferred embodiment, in which:

FIG. 1 is a diagrammatic view of a rolling seal diaphragm device;

FIGS. 2a, 2b, 2c, and 3 are corresponding diagrammatic views illustrating the effect of relative movement of piston and housing;

FIG. 4 is a vertical sectional view at 4—4 of FIG. 5; FIG. 5 is a sectional view at 5—5 of FIG. 4;

FIG. 6 is a vertical sectional view of the unconvoluted rolling seal diaphragm shown in FIG. 4; and

FIG. 7 is a partial, enlarged view, showing the initially snap-convoluble portion of the diaphragm of FIG. 6.

Referring now in greater detail to the drawings, there is shown in FIG. 1 a conical housing 10 and a conical piston 12, each defined by revolution, about a common vertical axis, of lines at 45° to the axis and at 90° to each other, with rolling seal diaphragm 14 convoluted therebetween to subtend an arc corresponding to said 90°.

The diaphragm preferably should be formed in manufacture with its inner surface of a configuration conforming, at least in part, to the outer configuration of the piston, making buckling in compression of at least this part (which in some embodiments may be most or almost all of the rolling wall) impossible in use. Although the diaphragm 14 is diagrammatically shown in FIG. 6, it actually includes a circumferentially compressed layer of fabric with interlocking fibers (woven or knitted), through the interstices of which have been forced an elastomer, all as described in detail in various aspects in my United States Patents Nos. 2,849,026, 3,083,734, and 3,137,215.

In the preferred embodiment shown, the fabric element is formed to the configuration shown by the upper and lower dotted lines of FIG. 6, taken with the intermediate solid lines into which the dotted lines merge. Then the fabric element (for example, of woven polyester) and elastomer (for example, acrylonitrile) are united, still retaining this same shape, and cured about 90% in a first mold having the configuration of the lower dotted lines of FIG. 6 and the solid lines thereabove into which said dotted lines merge. In completing the cure, the unit is formed between dies that impose on it its final convoluted stable configuration, as shown in FIG. 6, taking the dotted upper portion together with the solid lower portion 36 into which it merges. The resultant diaphragm is stable in both the final top hat configuration of the solid lines of FIG. 6 and the final convoluted stable configuration referred to.

The second molding step has the effect of imposing the reversely curved configuration shown in the enlarged detailed view of portion 38 of diaphragm 14 shown in FIG. 7. As will be seen, this portion is symmetrical about a reversely curved centerline defined by a pair of arcs of radii r (the radius of convolution of the diaphragm) of the same length (θ is the angle between the axis of the diaphragm and the radius r perpendicular to the surface of the piston 12 and housing 10), struck from centers on opposite sides of the wall, the arcs being of the same length and flowing into each other at a tangent to both. Furthermore, the head corner radius 50 is formed in its stable top hat configuration in the first molding step, but in its (reverse) stable convoluted configuration in the second molding step, as shown. This diaphragm may be snapped into convoluted form by an unskilled worker, even though unassembled to a piston or cylinder. It is bistable: that is, the diaphragm rests without outside application on it of any force, and relatively stress-free, in either top hat or stable convoluted configuration.

The reduction of stress owing to the very fact of convolution is itself an important factor in increasing flexibility, and an important feature of the novel diaphragm. From this standpoint either the intermediate portion's or the head corner radius' contribution is significant, aside from the other, but for best results the diaphragm should be manufactured so as to have the benefit of their joint contribution.

Stability in a convoluted position into which an unskilled assembly line worker can snap the diaphragm facilitates shipment of diaphragms separately, and in inexpensive nesting top hat configuration if desired, which is also of considerable practical importance. In preferred embodiments the rolling wall is tapered, say 6°, for this nestability, although the bistable character is of course important wholly aside from nestability.

Other embodiments than that shown will occur to those skilled in the art.

I claim:

1. A rolling seal diaphragm with a rolling wall including a longitudinally intermediate portion with a centerline including a pair of arcs of the same length and of radii of the same length, the radii being struck from centers on opposite sides of said wall.
2. The rolling seal diaphragm of claim 1 which is convolubly bistable around a head corner radius thereof.
3. The diaphragm of claim 1 in which said rolling wall is conical above and below said intermediate portion.
4. The diaphragm of claim 1 in which said arcs merge into each other along a tangent to both.

5. A rolling seal diaphragm device comprising a housing with a housing diaphragm support surface, a piston with a piston diaphragm support surface mounted for longitudinal movement in said housing, and a rolling seal diaphragm convoluted and secured around housing and piston ends respectively by said housing and said piston, said housing diaphragm support surface and said piston diaphragm support surface being defined by rotating a first and a second line respectively about a common longitudinal axis, said first line and said second line being each straight lines converging as extended in an acute angle in the direction that the radius of convolution of said diaphragm extends from the center of said radius to said convolution, at least a portion of the mating surfaces of said diaphragm and said piston being in fitting relation therewith while said diaphragm is unstressed around said portion, and said rolling seal diaphragm being bistable, having stability without stress in both top hat and convoluted configurations by virtue of

an unconvoluted configuration in which the diaphragm rolling wall includes a longitudinally intermediate portion having a centerline including a pair of arcs of the same length and of radii of the same length, said radii being struck from centers on opposite sides of said wall and said arcs merging into each other along a tangent to both, each said arc having a length half the arc length of said convolution, said radii being of the same length as said radius, said diaphragm being convolubly bistable around a head corner radius thereof.

6. A rolling seal diaphragm device comprising a housing with a housing diaphragm support surface, a piston with a piston diaphragm support surface mounted for longitudinal movement in said housing, and a rolling seal diaphragm convoluted and secured around housing and diaphragm ends respectively by said housing and said piston, the rolling wall of said diaphragm as manufactured having a longitudinally intermediate portion with a center line including a pair of arcs of the same length and of

radii of the same length, the radii being struck from centers on opposite sides of said wall, and said housing diaphragm support surface and said piston support surface being defined by rotating a first and a second line respectively about a common longitudinal axis, said first line and said second line converging as extended in an acute angle in the direction that the radius of convolution of said diaphragm extends from the center of said radius to said convolution, and each of said first and second lines defining an angle of at least 10° with said axis.
